UNITED STATES PATENT OFFICE.

MOSES C. MIGEL, OF NEW YORK, N. Y.

DESIGN FOR A PATTERN FOR SILK FABRIC.

SPECIFICATION forming part of Design No. 83,013, dated July 24, 1900.

Application filed June 16, 1900. Serial No. 20,603. Term of patent 3½ years.

To all whom it may concern:

Be it known that I, MOSES C. MIGEL, a citizen of the United States, residing in the city, county, and State of New York, have invented and produced a new and original Design for a Pattern for a Silk Fabric, of which the following is a specification.

The leading feature of my design is a pattern for a silk fabric, substantially as represented in the accompanying drawings and pointed out in the claim at the end of this specification.

In the drawings, Figure 1 shows the face of a pattern for a silk fabric embodying my design, and Fig. 2 is a view of the back.

The fabric body *a* is traversed in one di-

rection by substantially-parallel lines *b* and in the other direction by irregular stripes or bands *c*, which are salient on the face of the fabric and reentrant on the back. The lines *b* are formed in the body of the fabric and do not cross the bands *c* on the face of the fabric, but cross these bands on the back of the fabric in irregular twisted lines *b'*.

What I claim is—

The design for a pattern for a silk fabric, substantially as herein shown and described.

MOSES C. MIGEL.
